Primary Examiner — David G Muller(74) *Attorney, Agent, or Firm* — Greenberg Traurig, LLP(57) **CLAIM**

We claim the ornamental design for a ventilation grille, as shown and described.

DESCRIPTION

FIG. 1 is a perspective view of the ventilation grille.

FIG. 2 is bottom view thereof;

FIG. 3 is a front view thereof;

FIG. 4 is a rear view thereof.

FIG. 5 is a right side view thereof; and,

FIG. 6 is a left side view thereof.

The present application is directed to the shape and contour of the design illustrated in the drawings.
